UNITED STATES PATENT OFFICE.

EDWARD W. POWERS, OF BOSTON, MASSACHUSETTS, ASSIGNOR, BY MESNE ASSIGNMENTS, TO BENJAMIN FARNHAM SMITH, OF CONCORD, MASSACHUSETTS.

SPINNING RING.

Application filed June 3, 1921, Serial No. 474,619. Renewed July 14, 1923.

To all whom it may concern:

Be it known that I, EDWARD W. POWERS, a citizen of the United States, and resident of Boston, county of Suffolk, State of Massachusetts, have invented an Improvement in Spinning Rings, of which the following description, in connection with the accompanying drawing, is a specification, like characters on the drawing representing like parts.

10 This invention relates to spinning rings of that type which include a casing or holder which is provided with a bearing member or lining of self-lubricating material, and an annular traveller operating within the casing. Spinning rings of this type are illustrated in United States Patents Numbers, 857,535, dated June 18, 1907, 874,429, dated December 24, 1907, 957,759, dated May 10, 1910 and 1,333,072, dated March 9, 1920.

20 One of the objects of the present invention is to improve spinning rings of the above mentioned type by providing a spinning ring which can be manufactured at a considerably less cost than the spinning rings illustrated in said patents.

Another object of the invention is to provide an improved spinning ring of this type which comprises fewer parts and is simplified in construction.

30 Another object of the invention is to provide a spinning ring of this type which has an improved casing, an improved manner of supporting and retaining the traveller, an improved traveller in which the 35 stem carrying the guide eye has an inclination to the plane of the traveller and other features of importance all as will be more fully hereinafter set forth.

In order to give an understanding of my 40 invention I have illustrated in the drawings a selected embodiment thereof which will now be described after which the novel features will be pointed out in the appended claims.

45 Fig. 1 of the drawings is a plan view of a spinning ring embodying my invention.

Fig. 2 is a plan view of the base member.

Fig. 3 is an under side plan view of the upper member.

50 Fig. 4 is an under side plan view of the self-lubricating member showing the manner in which the traveller is retained in place.

Fig. 5 is an enlarged section on the line 5—5, Fig. 1.

Fig. 6 is an enlarged section on the line 55 6—6, Fig. 1.

Fig. 7 is a side view of the traveller showing the inclination of the stem.

Fig. 8 is a fragmentary view of the lining member showing the manner in which the 60 supporting pins are connected thereto.

In my present invention I have simplified the construction of the holder or casing in which the traveller is received by making it of a base member, an upper member which is frictionally held to the base member and a self-lubricating bearing member which is received between the base member and the upper member. 1 indicates the base member of the casing, 7 indicates the upper member 70 of the casing, 8 indicates a lubricating lining member and 9 indicates the traveller. This base member 1 is formed with a base flange 2 adapted to rest on and be secured to the ring rail of the spinning frame. This 75 flange will preferably be provided with a plurality of notches 3 to receive screws or other fastening means for retaining the base to the ring rail. The base member is an annular member provided with central opening 5 80 and it is made of sheet metal which is deformed by means of suitable dies so as to present the inwardly-directed supporting flange 4 that is situated above the base flange 2 and which constitutes a support for the self- 85 lubricating member. The base member is also deformed to present the annular rib 6 which constitutes the portion to which the upper member 7 is secured. This upper member 7 is an annular member and is 90 formed from sheet metal, it being provided with the side walls 10 and the inwardly-directed flange 11 at its upper end. The lower end of the side walls 10 are so arranged 95 that they can be snapped over or frictionally secured to the bead 6 of the base member. This is accomplished by crimping inwardly certain parts of the lower edge of the member 7 as shown at 12, such inwardly-crimped portions being constructed so that they may be 100 sprung over the bead 6 as shown in Fig. 5. In the preferred embodiment of my invention I form the lower edge of the member 7 with outwardly-bent portions 13 which separate the inwardly-crimped portions 13. 105 With this arrangement the separated inwardly-crimped portions 12 are free to expand slightly when the upper member 7 is applied

to or removed from the base member 1. The outwardly-bent portions 13 also provide spaces 14 between the stem and the flange 2 into which an implement may be inserted 5 for prying the members 1 and 7 apart.

The lining member 8 is made of some self-lubricating material such for instance as wood treated in oil and it is confined between the flange 4 of the base member and 10 the flange 11 of the upper member as clearly seen in Fig. 5. This lining member is an annular member and is formed with the space 15 in which the traveller 9 is received and is also provided with the inwardly-directed flange portion 16 which overlies the traveller 9 and the under face 17 of which 15 forms a bearing for the traveller when the latter is raised. The traveller 9 is of the annular type and is provided with the stem 20 which extends upwardly through the bearing member and is formed with a guide eye 19 at its upper end.

In my present invention the stem 18 is inclined to the plane of the traveller, the 25 inclination being such that the stem inclines forwardly toward the direction in which the traveller is rotating. This is seen in Fig. 7. The purpose of this construction is to so distribute the strain of the yarn on the traveller that it will not tend to distort the traveller as is the case where the stem extends vertically. These travellers are made of quite thin stock and the strain of the yarn tends to throw the stem out of a true vertical position and thus distort the body of 30 the traveller. I find that by making the stem with this inclination such tendency is largely eliminated.

When the spinning ring is in use the 40 traveller is rotating rapidly in the space 15 and the strain of the yarn tends to keep it at the upper portion of such space adjacent to the surface 17. Some means has to be provided, however, for supporting the traveller 45 when the spinning ring is idle or at rest and in my present construction such support is secured to and sustained by the lining member 8. While various types of supporting the traveller from the lining member 50 may be employed without departing from my invention yet the construction illustrated herein is a simple one which has the advantages that it is inexpensive to manufacture, that it provides for easy removal 55 from the lining member or insertion of the traveller in its place, and it is self-cleaning and does not collect lint. Said traveller support comprises a plurality of arms 20 which are carried by the lining member and projected sufficiently into the space 15 to constitute a support for the traveller. I prefer 60 to place these supporting pins so that they have a tangential arrangement relative to the traveller as indicated best in Fig. 4, the 65 free ends of said pins being pointed in the

direction in which the traveller is rotating which in Fig. 4 would be in the direction of the arrow. Such pins furnish a suitable support for the traveller but they leave the space beneath the traveller open and free 70 so that any lint will be freely discharged from said space. Owing to the tangential arrangement of the pins or arms 20 and their relation to the direction of rotation of the traveller there is no possibility that 75 any lint will collect on the arms for if any lint should find its way into the space 15 such lint will be wiped off the arms by the rotary motion of the traveller and will be discharged at the free open space at the bottom of the spinning ring.

In order to facilitate the removal of the traveller from the lining member 8 or its insertion into place I propose to pivotally mount the arms 20 in the lining member so 80 that they can be swung back into the dotted line position Fig. 4 when the lining is removed from the casing. For this purpose each arm is provided with the laterally bent end 21 which is inserted into and pivotally mounted in a bore 23 formed in the lining member. The lining member is formed with the notch 22 at the point where each arm is pivotally connected thereto and the bore 23 into which the end 21 is received extends 90 from one wall of the notch. The lining member is grooved as shown at 24 to receive the arm when the latter is in its operation position, the groove being of sufficient depth so that the arm is entirely above the plane 95 of the lower face of the lining member. So long as the arms are in the full line position Fig. 4 they are operative to hold the traveller in position but by swinging two or more of the arms backwardly into the 100 dotted lines position the traveller is free to be removed from the lining member.

It will be noted that the spinning ring holder or casing in which the traveller is received comprises merely the base member 110 1, the upper member 7 and the lining member 8. Said holder therefore has a minimum number of parts which is conducive to cheapness of manufacture. Furthermore the manner in which the parts are constructed reduces the cost of manufacture. 115

I claim:

1. In a spinning ring, the combination with a base member adapted to be attached to the ring rail of a spinning frame, of an upper member having its lower edge telescoped over and frictionally engaging a portion of the base member, a self-lubricating lining member confined between the base member and the upper member and provided with a traveller-receiving recess and an annular traveller situated in said recess. 120

2. In a spinning ring, the combination with a base member having a base flange adapted to rest on and be secured to the 125

ring rail of a spinning frame, said base member having an annular raised portion provided with an inwardly-directed annular supporting flange, of a self-lubricating lining member resting on said flange, an upper member partially enclosing said lining member and having its lower portion telescoped over and frictionally engaging the raised portion of the base member, and an annular traveller situated within the lining member.

3. In a spinning ring, the combination with a base member adapted to rest on and be secured to the ring rail of a spinning frame, said base member having an annular inwardly-directed flange and a bead at the periphery of the flange, of a self-lubricating lining member resting on the flange, an upper member partially enclosing the lining member and constructed to be snapped onto said bead and a traveller situated within the lining member.

4. In a spinning ring, the combination with a base member having an annular bead on its periphery, of a self-lubricating lining member supported by the base member, an upper member partially enclosing the lining member and provided with means to frictionally engage the bead and an annular traveller within the lining member.

5. In a spinning ring, the combination with a base member having an annular bead and a supporting flange, of a self-lubricating lining member resting on said flange, an upper member partially enclosing the lining member and having at its lower edge separated inwardly-crimped portions to frictionally engage the bead, and an annular traveller situated within the lining member.

6. In a spinning ring, the combination with a base member, of a self-lubricating lining member supported by the base member, an annular traveller situated within said lining member, and a plurality of supporting members carried by the lining mem-

ber for supporting the traveller when it is at rest.

7. In a spinning ring, the combination with a base member, of a self-lubricating lining member supported by the base member and provided with a traveller-receiving recess, an annular traveller in said recess, and supporting arms carried by said lining member for retaining the traveller in the recess.

8. In a spinning ring, the combination with a base member, of a self-lubricating lining member supported by the base member and provided with a traveller-receiving recess, an annular traveller in said recess, and supporting arms carried by said lining member for retaining the traveller in the recess, said arms having a tangential arrangement relative to the traveller.

9. In a spinning ring, the combination with a base member, of a lining member sustained by the base member and provided with an annular traveller-receiving recess, an annular traveller in said recess, and arms pivotally mounted to the lining member and when in operative position being situated beneath and supporting the traveller.

10. In a spinning ring, the combination with a base member, of an annular lining member sustained thereby, an annular traveller operating within the lining member and a plurality of supporting members independent of said base member for supporting the traveller when the ring is idle.

11. In a spinning ring, the combination with a base member, of a self-lubricating lining member supported by the base member, an annular traveller situated within the lining member, and means movably carried by the lining member for supporting the traveller when it is at rest.

In testimony whereof, I have signed my name to this specification.

EDWARD W. POWERS.
